ABSTRACT: A device for making a culture of micro-organisms has an elongated member which advantageously supports a culture medium on each of two opposite flat faces. A container having an open end is provided for the elongated member. A brush mounted in the container contacts the elongated member intermediate its ends. The open end of the container has removable means to seal it. In a typical operation, the elongated member is removed from the container and the end thereof brought into contact with the area of the patient suspected of having micro-organisms. On returning the elongated member to the container it passes the brush which wipes along the member to brush the inoculum from the end along the culture medium. Advantageously, the container has a guide member to guide the elongated member and restrict its movement toward the interior surfaces of the container. Preferably the brush forms a part of the guide member and the elongated member has a plug adapted to form a seal with the guide member to permit the withdrawal of the elongated member from the container either independently of the guide member or together with the guide member.

DEVICE FOR MAKING A CULTURE OF MICRO-ORGANISMS

BACKGROUND OF THE INVENTION

Devices for making a culture of micro-organisms having a culture medium which can be brought directly into contact with an area of a patient's body and then returned to a sealed container for growing micro-organisms picked up are known to the art as is seen, for example, in the disclosure of U.S. Pat. No. 3,368,549, issued Feb. 13, 1968. Such devices have as their intended purpose providing office diagnosis within 24 hours without the necessity for a laboratory. In heretofore known devices there has been difficulty in assessing the results achieved due to the fact the inoculum is heavily concentrated in a single area and dilution is not possible. Isolated colonies are not seen because of restricted surface area. Further, difficulty has been encountered due to the fact that the inoculated culture medium comes into contact with the sides of the container and permissible movement disrupts growth of micro-organisms. In addition, the visibility through the container has been poor. All of these problems are solved in the present invention.

SUMMARY OF THE INVENTION

A device for making a culture of micro-organisms has an elongated support member which carries a culture medium supported by said member preferably intermediate the ends thereof. A container having an open end is adapted to contain the elongated member and has a brush mounted therein to brush over the inner end of the elongated member and at least a portion of the culture medium on insertion of the elongated member into the container. Preferably the container is transparent and has flat surfaces through which the culture medium is viewed. A seal for the open end of the container is provided and it advantageously forms a part of the elongated member. Advantageously a hollow guide member guides the elongated member within the container to restrict its movement towards the interior surfaces of the container. Preferably the brush forms a part of said guide member and the elongated member has a plug engaging the guide member to seal the container. Advantageously the guide member is removable.

DESCRIPTION OF THE DRAWINGS

FIG. 1 is an elevational view of a prior art device;

FIG. 2 is an elevational view of a device in accordance with the invention;

FIG. 3 is a vertical section taken on the plane indicated by the line 3—3 in FIG. 2;

FIG. 4 is an end of view of the guide member and brush of the device of FIG. 2;

FIG. 5 is a side elevation of the structure of FIG. 4;

FIG. 6 is a top plan view of the elongated support member of the device of FIG. 2 without the culture medium;

FIG. 7 is a top plan view, partially broken away, of the member of FIG. 6 with the culture medium added;

FIG. 8 is a top plan view, partially broken away, of an alternative elongated member having culture medium extending about the inner end;

FIG. 9 is an exploded broken away view of the device of FIG. 2; and

FIG. 10 is an exploded perspective view of the elongated member and the guide member and brush illustrating the spreading of the inoculum. Prior Art

A typical prior art device is shown in FIG. 1. Here a glass container tube 2 has a threaded cap 4 and contains a stick 6 having a frame end 8 for the support of a solid culture medium 10. It will be noted that the end portion 12 of the culture medium 10 is in contact with the interior surface of the container 2.

Preferred Embodiment of the Invention

Referring now to FIG. 2 a device 20 for making a culture of micro-organisms in accordance with the invention has a transparent container 22 of, for example, glass or a plastic such as an acrylic resin such as methyl methacrylate or a polycar-

bonate resin. As shown in FIGS. 6 and 7, an elongated member 24 has an inner end 28 and a recessed portion 26 in opposed substantially flat faces (only one being shown). Each recessed portion is intermediate the ends of the elongated member 24 and has multiple small protrusions 30 to facilitate the retention of a body 32 of a solid culture medium in the recessed portions. The culture medium is preferably flush with the adjoining portions the adjacent face 28.

The side edges of elongated member 24 are guided by opposed grooves 36, 36 in hollow guide member 38 which has a cylindrical portion 40 (FIG. 5) provided with ridges 42 which sealingly engage a cylindrical entrance portion 44 of container 22. Guide member 38 is also provided with opposed flats 46, 46 which engage the flat top 48 and the flat bottom 50 of container 22 (FIGS. 9 and 10). The inner end of guide member 38 has a pair of opposed brush members 52, 52 positioned adjacent grooves 36, 36 so as to engage elongated member 24 as it is inserted into container 22. Each brush member 52 has three spaced projections 54 for engaging the elongated member 24.

Guide member 38 has a cylindrical entrance portion 56 which is engaged by a plug portion 58 (FIG. 10) of member 24 having a peripheral ridge 60 to seal closed the end of guide member 38. The outer end of elongated member 24 is in the form of handle 64.

Advantageously the guide member will be made of a resilient plastic such as, for example, polyethylene or polypropylene and the brush member 52, 52 will be integral therewith permitting the formation of the guide member and the brush members in a single forming operation from the same material.

The culture medium will be selected depending upon the micro-organisms involved. Suitable solid culture mediums are well known to the art. Reference may be had, for example, to the culture mediums disclosed in U.S. Pat. No. 3,368,549 the disclosure of which is incorporated herein by reference. Agar culture mediums are preferred since their solidity is readily controlled by varying the percent of Agar. Further typical culture mediums are set forth below:

- A. Moni-Tube—for isolation and presumptive identification of *Candida*
Media—BIGGY Agar (formerly Nickerson)

	Formula
Distilled water	1 l.
Bismuth Ammonium Citrate	5 g.
Sodium Sulfite	3 g.
Dextrose	10 g.
Glycine	10 g.
Yeast Extract	1 g.
Agar	2.0% of weight of the total formula.

B. Hemolytic Tube—for isolation and presumptive identification of B-Hemolytic Streptococci
Media—Trypticase Soy Agar with 5% Defibrinated Sheep blood.

	Formula
Distilled water	1 l.
Trypticase Peptone	15 g.
Phytone Peptone	5 g.
Sodium Chloride	5 g.
Agar	3.0% by weight of the total formula.
Defibrinated Sheep blood	5% by weight of the total formula.

C. Bacteruria Tube—for isolation 1 l. bacteria from urine.
Media—Eosin Methylene Blue Agar

	Formula
Distilled water	1 l.

Distilled water	1
Peptone (Gelysate)	10.000 g.
Lactose	5.000 g.
Sucrose	5.000 g.
Dipotassium Phosphate	2.000 g.
Eosin Y	0.400 g.
Methylene Blue	0.065 g.
Agar	1.3% by wt.

Different formulae can be used on opposite sides of the elongated member for example, the formula of A above on one side and the immediately above formula on the other side.

OPERATION

In operation the elongated member 24 is removed from container 22 by withdrawing through guide member 38. The end 25 is brought into contact with the area of the patient which is suspected of having relevant micro-organism. The elongated member is then returned into container 22 with grooves 36, 36 guiding it through brushes 52, 52 and preventing it from touching the interior surfaces of container 22. As the end 25 of elongated member 24 passes through brushes 52, 52 the portions 54 wipe the inoculum from end 25 onto the bodies 32, 32 of culture medium carried in the recessed portions 26, 26 in faces 28, 28. As illustrated in FIG. 10 this results in placing three straight lines 68, 70 and 72 of inoculum on each body of culture medium which dilutes the inoculum and provides isolated colonies.

If it is desired to closely inspect the elongated member 24 during the growth of micro-organisms this can be done readily by removing the member 24 together with the guide member 38 thus preventing brushes 52, 52 from further brushing the culture medium.

ALTERNATIVE EMBODIMENT

Referring now to FIG. 8, if desired, a modified elongated member 80 can be employed. Member 80 is the same as member 24 but provides for a body 82 of culture medium on both sides (only one side being shown) which extends beyond the inner end of member 80 as indicated at 84. To facilitate

40

this arrangement, the body 82 of culture medium is carried in a recessed portion 86 on each side, protrusions 88 being employed to assist in retaining the body of culture medium. Each recessed portion 86 extends to the end 90 of member 88.

5 The above-described embodiments are illustrative and are not intended to be limiting.

We claim:

1. A device for making a culture of micro-organisms comprising: an elongated member, a culture medium supported by 10 said member intermediate the ends thereof, a container for the elongated member having an open end, brush means mounted in the container and positioned for contacting the elongated member intermediate its ends so as to brush over at least a portion of the culture medium on insertion of the elongated member into the container and means to seal the open end of the container.
2. The device of claim 1 in which the culture medium extends to and covers at least a portion of the inner end of the elongated member.
- 15 3. The device of claim 1 in which the sealing means includes a plug on the elongated member.
4. The device of claim 1 in which the brush is removably mounted adjacent the open end of the container.
5. The device of claim 1 in which a hollow guide member is 20 mounted in the open end of the container to guide the elongated member and restrict its movement towards the interior surfaces of the container.
6. The device of claim 1 in which a body of culture medium is supported on each of two opposite sides of the member 25 elongated.
7. The device of claim 6 in which the culture medium bodies on opposite sides of the elongated member are different.
8. The device of claim 6 in which the guide member is 30 removable.
9. The device claim 1 in which the container is transparent.
10. The device of claim 9 in which the container has a flat portion opposite the elongated member for viewing the culture medium.
